SEWING MACHINE

Henry J. Ernst, Southgate, Ky., assignor of one-half to Edward C. Ernst, Newport, Ky.

Application December 2, 1933, Serial No. 700,726

14 Claims. (Cl. 112—130)

My invention relates primarily to sewing machines adapted for the sewing of a tape or strip upon a fabric, body or work piece. For the purpose of a disclosure of my invention, I shall describe it in an exemplary embodiment which has to do with the sewing of channel tape on the insoles of shoes. In one type of shoe manufacture a channel tape is sewed to the insole, and the upper is in turn attached to this channel tape.

Hitherto it has been the practice to run the insole through the machine bottom side up, and sew the tape thereto from above. This has certain disadvantages inherent both in the process and in the apparatus used to perform it. When the tape is sewed to an insole which lies below it during the sewing operation, the result of the sewing is to tend to warp the insole so that it becomes concave as viewed from above. This requires an additional operation to straighten the insole. Again, the operation of sewing tape on to an insole which lies beneath the tape during the sewing operation necessitates the provision of feeding means for the tape located above the work. This is inconvenient and cumbersome and frequently precludes the use of desirable mechanical adjuncts such as means for severing the tape and automatic or semi-automatic means for feeding it when desired.

It is therefore an object of my invention to provide a type of sewing machine in which the tape will be guided beneath the insole or other work piece into a proper position for sewing, thus permitting the needle to penetrate first the work piece and then the tape.

It is an object of my invention to provide means for guiding the tape positively, so that not only will it be caught by the needle but so that the line of stitching formed in the tape may be properly positioned therein. It will be understood that in sewing channel tape to insoles, it is desirable to have the line of stitching come nearer one edge of the tape than the other so as to leave one edge of the tape free for the adjustment of the upper.

It is another object of my invention to provide auxiliary feeding means for the tape in the preferred form of my invention, so that when the operator releases the tape for feeding it will be fed into a position to be caught by the line of stitching without any supplementary action on the part of the operator.

It is also an object of my invention to provide means whereby the operator can render the supplementary feeding means inoperative so that

stitching can be done without including the tape, while the tape will be held in a position for further feeding when desired.

Another object of my invention is to provide means for cutting the tape, which means as will hereinafter be set forth, have a novel mode of operation.

Another object of my invention is to provide means for raising the presser foot or roll and cutting the tape by one motion of the operation, these means being of a character to permit a variable lapse of time between the operations just referred to.

It is still another object of my invention to provide variable and adjustable guiding means for the insole or other work piece, whereby the operator can insure the provision of the desired uniform or variable margin between the tape and the edge of the work piece.

This and other objects of my invention which will be set forth hereinafter or will be apparent to one skilled in the art upon reading these specifications, I accomplish by that certain construction and arrangement of parts of which I shall now describe a preferred embodiment.

Reference is now made to the drawings which form a part hereof and in which:

Figure 1 is a perspective view of a sewing machine embodying my invention.

Fig. 2 is a plan view of the table showing the throat plate and sole guiding means, with parts cut away to show the construction.

Fig. 3 is a sectional view taken on the line 3—3 of Fig. 2.

Fig. 4 is a sectional view of the sole guide taken on the line 4—4 of Fig. 2.

Fig. 5 shows the underside of a special type of insole with the attaching tape stitched in place.

Fig. 6 is a sectional view of the tape cutting mechanism, taken on the line 6—6 of Fig. 2.

Fig. 7 is a plan view of the throat plate in a modified form of my invention.

Fig. 8 is a sectional view on the line 8—8 of Fig. 7.

Fig. 9 is a sectional view on the line 9—9 of Fig. 7.

Fig. 10 is a perspective view of the guide and knife of the modification shown in Figs. 7 to 9.

Fig. 11 is a plan view of the throat plate in another modification.

Fig. 12 is a sectional view on the line 12—12 of Fig. 11.

Fig. 13 is a perspective view of the cutter employed in the modification shown in Figs. 11 and 12.

Briefly, in the practice of my invention, I provide a sewing machine of conventional design, illustrated generally at 1. This machine has a needle 3, and a presser wheel 4. The insole being 5 sewed is indicated at 5, and the tape which is to be sewed to it is shown at 6.

The feed mechanism, best shown in Fig. 3, comprises an oscillating link 7 pivoted at 10, an oscillating link 8 pivoted at 11, and the feed bar 9, 10 pivoted at the free ends of links 7 and 8, at 14 and 15 respectively. The directions of oscillation of links 7 and 8 are indicated by arrows. The toothed feed dog 13 is fastened to the feed bar 9 by means of the screws 12. The motion of 15 the feed dog 13 resulting from those impressed upon links 7 and 8, is upward, then to the left, then downward and then to the right, roughly counterclockwise. The pivoted connection at 15 has been shown variable, in order to permit of an 20 adjustment of the stroke of the feed dog.

A guide, indicated generally at 16, is provided to direct the tape into the machine and up through a hole 17 in the throat plate 18. At the entrance of this guide, a roller 16a is provided to 25 reduce frictional wear on the tape. A toothed tape feed dog 19 is attached to the feed bar 9 by the screw 20, and operates through an opening 21 in the guide 16. Pivoted at 22 within the guide 16, is a rocking lever 23. The end 25 of this 30 lever provides a backing for the feed dog 19, and the other end terminates in a prong 24. The lever 23 is maintained in the position shown in Fig. 3 by means of a tension spring 26, attached at one end to the frame of the machine at 27 and 35 at the other end to the pin 28 which is rigidly mounted in the lever 23. The pin 28 projects through a sector slot 29 in the guide 16. A rod 30 is journaled under the bed of the machine at 31 and 32 (Fig. 2). The end 33 of rod 30 is bent 40 at a right angle to the main part of the rod, and the torsion spring 35 keeps the rod 30 turned so that its end 33 is maintained out of contact with the pin 28. The other end 36 of the rod 30 is also 45 bent at right angles to the main part of the rod, but in the opposite direction to the end 33, and is provided with a push button 34 which projects through the table of the machine.

Pressure exerted by the operator on push button 34 rotates the rod 30 in such a manner 50 that the end 33 is moved upward, pushing before it pin 28 against the tension of spring 26. This rocks lever 23 clockwise a slight amount, raising the presser 25 and bringing the prong 24 down onto the tape. Thus when the tape has been cut, 55 the effectiveness of the feed dog 19 is nullified, and the tape is restrained from any further advance into the machine, or from falling out of the guide.

In the stitching operation it is desirable to have 60 the seam follow the outlines of the insole at a variable distance from its edge. To this end I provide a guiding device indicated generally at 7 in Fig. 1. Referring more particularly to Figs. 2 and 4, I provide a base plate 38 and a cover plate 39, held apart by spacers 40, and all fastened together and to the machine table by the screws 41.

The spacers 40 together with the base plate 38 70 and the cover plate 39, form a guide within which a bar 42 is slidably retained. The bar 42 is provided at its right hand end with a shoulder 43, and along one edge near its center, with the rack teeth 44. The torsion spring 45, fastened to the machine table by means of a screw 46, and having 75 its other end seated in a hole 47 in the shoulder

43, tends to keep the bar 42 at the right hand limit of its travel. A pinion 48 is also mounted on a shaft 49 between the base plate 38 and the cover plate 39, and meshes with the rack 44 in the bar 42. A driving force imparted to the shaft 5 49 is transmitted to the pinion 48 by means of a set screw 50 in the hub 51 of the pinion 48, so that upon rotation of the shaft 49 in a clockwise direction (Fig. 2), the bar 42 will be slid to the left. Any suitable means of motivation may be 10 provided for the shaft 49, such as a foot pedal or knee press, and the connections to such means are indicated generally at 52.

A guide roll support 53 is hinged to the bar 42 near its left hand end by means of the pin 54, 15 and the roll 55 is rotatably mounted on a vertical pin through the left hand end of the support 53. A heavy wire lifter foot 56, the function of which will be described later, is soldered onto the left hand end of the support 53. Mounted on the bar 20 42 near the pivot 54 by means of the screw 59, is an angle piece 57 forming an upstanding shoulder, and a flat spring 58. The purpose of the spring is to keep the support 53 in the position shown in Fig. 4. The cover plate 39 is slotted as at 60 to provide clearance for the upstanding shoulder 57 on the bar 42, and a part of the cover plate which formerly occupied the space 60 is turned up vertically to form an upstanding lug 61. A second upstanding lug, similar to lug 61 is provided at the other end of the cover plate at 62. Mounted in these upstanding lugs 61 and 62 are adjusting screws 63, provided with lock nuts 64. By an adjustment of screws 63, the operator may define the extent of variation of the margin between the seam and the edge of the insole. Thus by the operation of a pedal or knee-press (not part of this invention, and therefore not illustrated) the above-mentioned margin may be varied. A release of pressure on the pedal or knee-lift causes a movement of the gear 48 in a 30 counterclockwise direction, which will slide the bar 42 toward the right, aided by the action of the spring 45, thereby increasing the margin between the seam and the edge of the insole, until the shoulder 57 strikes its stop pin 63, defining the maximum margin; the above motions are 35 reversed when pressure is applied to the pedal or knee-press against the tension of the spring 45, until the shoulder 43 strikes its stop pin 63, defining the minimum margin. 40

If soles are being made for a shoe with a built in arch support, another problem arises. A sole of this type is illustrated in Fig. 5, and it will be seen that such a sole has a salient portion 65. 55 It will also appear from a study of this figure, that the seam 6 does not follow the outline of this salient portion, and that therefore the margin between the edge of the insole and the seam at this point is substantially greater than any 60 variation permitted by the above described device. At this stage, the utility of the wire lifter foot 56 becomes apparent. This member 56, seen in elevation in Fig. 3, has an upturned toe portion, so that if, when the salient portion 65 of 65 the sole is reached, the operator will manually guide the sole straight into the machine, the lifter foot 56 will ride up over the portion 65 and raise the arm 53 with its guide roll 55 against the action of the spring 58, and thus remove the 70 roll from its operative position, permitting the sole to be fed straight into the machine, regardless of the marginal limitation imposed by the adjustment of the screws 63. The portion 65 of the insole is usually skived to a bevel, which 75

greatly assists the foot 56 in surmounting this obstacle.

I shall now proceed to a description of the tape cutting mechanism, best illustrated in Fig. 6. A rod 66 is reciprocably mounted in a bearing 85 in the frame of the machine below the table. A cutter supporting bracket 67 is attached to the left hand end of the rod 66 by means of a screw 68, and the knife 69 is mounted upon the bracket 67 by means of the screws 70. A helical spring 80 attached to the right hand end of the rod 66, and to the frame by the screw 81, tends to keep the rod 66 in the position shown in Fig. 6. A stop collar 71 is provided to limit the cutting stroke of the knife, and a collar 72 with a lug 73 is adjustably mounted on the rod 66. The connecting link 75 has a transverse hole through its left hand end, into which the lug 73 is fitted, and retained by a cotter pin 74. Member 75 is provided with a longitudinal hole 76. The rod 77 is threaded over approximately two-thirds of its length, and ground to slidably fit the bore 76 in the member 75 at its other end. A pair of lock nuts 79 are threaded onto the rod 77, and the ground end is inserted into the bore 76 in the member 75. The right hand end of the rod 77 is attached to the usual knee lift operated presser wheel control, 83, 84.

The operation of this device is as follows: An outward pressure on the right knee lift rotates the rod 84 in a counter-clockwise direction and is immediately effective to start the presser wheel 4 upward. The counter-clockwise rotation of the rod 84 is transmitted to the rod 83, with the result of moving the rod 77 toward the left. By reference to Fig. 6 it will be seen that this movement has no effect other than to slide the rod 77 into the bore 76 until the lock nuts 79 abut the member 75. At this point the motion begins to be transmitted to the rod 66 and through it to the knife 69, against the tension of the helical spring 80. This mechanism insures that the presser wheel 4 is raised from the work before the knife 69 begins its cut. The length of time which is to elapse between the operations aforesaid may be varied by the adjustment of the lock nuts 79 on the thread 78.

Figs. 7 to 10 illustrate one modification of my invention. Here the cutting device previously described is simplified. The throat plate is made in two sections 86 and 87, and two slots 88 and 89 are milled in section 87 at right angles to each other. When the sections 86 and 87 are assembled, these slots form guides, slot 88 for the tape, and slot 89 for the cutter. A hole 90 communicates with the guide 88, for the purpose of bringing the tape out onto the top of the throat plate, and a resilient checking strip 92 projects through a hole 91 in the section 87, out into the guide 88. This strip prevents the tape from sliding backward when it is severed. Slider 93 is reciprocably mounted in the guide 89. This slider is provided with a wedge-shaped end 96, which acts as a guide to assist in forcing the tape up through the hole 90 (Fig. 8). Upon the slider 93 is mounted the knife 94, by means of the screws 95, and the slider is provided with a knob 97, which projects up through the slot 98 in the section 86. In this modification it is merely necessary to push the knob 97 toward the left, in order to sever the tape.

A slight modification of the device just described, is illustrated in Figs. 11 to 13. Here again the throat plate is made in two sections 99 and 100. A tape slot 101 is milled in the sec-

tion 100, and the tape is brought out onto the top of the throat plate through a communicating hole 102 in the section 99. An irregular clearance space 110 (outlined by broken lines in Fig. 11), is milled in the underside of the section 99. The member 104, drilled at 105, is provided at one end with a cutting edge 107, and at the other end with a knob 108 which projects through a sector slot 109 in the section 99. The member 104 is mounted between the sections 99 and 100, and pivoted at 106 so as to oscillate in the clearance space 110 within the limits of the sector slot 109.

In sewing the attaching tape to the insole on my machine, assuming that a sole has just been finished, and the tape has been cut, I place the new sole in position and start the machine. Several stitches will be made in the insole alone before the tape has been advanced sufficiently to be engaged by the needle. I now move the pedal or knee press controlling the guide, so that the margin between the seam and the edge of the insole conforms to specifications. When I reach the end of one seam, I stop the machine momentarily, push the right hand knee press outward cutting the tape, and then press the button 34 preventing the tape from further advancing into the machine. I then restart the machine and continue until the needle takes three or four stitches past the end of the tape. Then I turn 30 the sole, position it, release the button 34 and continue as above. The fact that several additional stitches are taken beyond the end of the tape at each end, insures that these ends are firmly sewed, and will not easily tear out.

It is to be understood that different forms of my preferred embodiment may be made without departing from the spirit of my invention.

Having thus described my invention, what I claim as new and desire to secure by Letters Patent, is:

1. In a sewing machine, the combination of a throat for the passage of a tape, said throat being adapted to guide said tape into a position for sewing, a main sewing machine feed and a supplementary feed for moving a tape in said throat, means for rendering said second feed inoperative on said tape, said means concurrently acting to prevent a withdrawal of said tape from said throat.

2. In a sewing machine, a throat for feeding and guiding tape in a position to be sewn, and means for severing said tape along a plane at an acute angle to the general plane of said tape, said means comprising a knife movable in a substantially horizontal plane.

3. In a sewing machine, a throat for guiding a tape into a position to be sewn to an overlying work piece, said throat adapted to permit the passage of said tape in a substantially horizontal plane but to bend said tape out of said plane and into a second displaced substantially horizontal plane, and a substantially horizontally movable knife adapted to sever said tape in the bent portion thereof.

4. In a sewing machine, a throat for feeding and guiding a tape in a position to be sewn to an overlying work piece, a main feed dog for said sewing machine, a supplementary feed dog for feeding said tape to said throat, and means for engaging said tape in said throat for alternatively pressing said tape against said supplementary feed dog or releasing said tape therefrom and engaging said tape against withdrawal from said throat.

5. In a sewing machine adapted for sewing tape on a superposed work piece, guide means for said tape adapted to deliver said tape into a position to be sewn, a severing means for said tape comprising a substantially horizontally reciprocating knife adapted to make a beveled cut in said tape, and operating means for said knife adapted to be actuated by an operator at will.
6. In a sewing machine adapted for sewing tape on a superposed work piece, guide means for said tape adapted to deliver said tape into a position to be sewn, a severing means for said tape comprising a substantially horizontally reciprocating knife adapted to make a beveled cut in said tape, and operating means for said knife adapted to be actuated by an operator at will, a presser foot for said sewing machine, and an operative connection between said severing knife and said presser foot for producing coaction thereof.
- 10 7. In a sewing machine adapted for sewing tape on a superposed work piece, guide means for said tape adapted to deliver said tape into a position to be sewn, a severing means for said tape comprising a substantially horizontally reciprocating knife adapted to make a beveled cut in said tape, and operating means for said knife adapted to be actuated by an operator at will, a presser foot for said sewing machine, and an operative connection between said severing knife and said presser foot for producing coaction thereof.
- 15 8. In a sewing machine, a throat plate, a channel in said throat plate adapted to deliver a tape into a position for sewing, feed means for said tape, and means in said throat plate for preventing the rearward withdrawal of said tape while permitting its forward movement, said last mentioned means becoming operative only upon the rendering inoperative of said feed means.
- 20 9. In a sewing machine, a throat plate, a channel in said throat plate adapted to deliver a tape into a position for sewing, said means adapted to bend said tape out of one horizontal plane for delivery into an opposite horizontal plane, and a knife movable in said throat plate for severing said tape in the bent portion thereof.
- 25 10. In a sewing machine, a tape guiding member lying within a channel in the bed of said sewing machine, said member having means for guiding a tape into a position to be sewn and for bending said tape while so guided, and a knife movable to make a beveled cut in said tape in the bent portion thereof.
- 30 11. In a sewing machine, a tape guiding member lying within a channel in the bed of said sewing machine, said member having means for guiding a tape into a position to be sewn and for
- bending said tape while so guided, and a knife movable to make a beveled cut in said tape in the bent portion thereof, a main feed means for said sewing machine, and a supplementary feed means for engaging said tape in said guiding 5 means.
12. In a sewing machine, a tape guiding member lying within a channel in the bed of said sewing machine, said member having means for guiding a tape into a position to be sewn and for bending said tape while so guided, and a knife movable to make a beveled cut in said tape in the bent portion thereof, a main feed means for said sewing machine, and a supplementary feed means for engaging said tape in said guiding 10 means, a tiltable member in said guiding means, one end thereof being adapted to press said tape against said feed means, the other end thereof being adapted alternatively to engage said tape to hold it from withdrawal from said guiding means when released from said feed means, and operating means for said tiltable member having means for engagement for actuation by an operator.
13. In a sewing machine, a tape guiding member lying within a channel in the bed of said sewing machine, said member having means for guiding a tape into a position to be sewn and for bending said tape while so guided, and a knife movable to make a beveled cut in said tape in the 15 bent portion thereof, a main feed means for said sewing machine, and a supplementary feed means for engaging said tape in said guiding means, a tiltable member in said guiding means, one end thereof being adapted to press said tape against 20 said feed means, the other end thereof being adapted alternatively to engage said tape to hold it from withdrawal from said guiding means when released from said feed means, operating means for said tiltable member having means for engagement for actuation by an operator, and means for normally holding said tilting member in tape feeding position.
14. In a sewing machine adapted for sewing tape on a work piece, means for guiding said tape 25 into a position to be sewn, said means comprising a throat means and means for preventing rearward withdrawal of said tape therefrom, means for severing said tape with a beveled cut as said tape is so guided, operating means therefor accessible to the operator of said sewing machine, and a guide for the work piece overlying said tape, said guide comprising movable means, operating means therefor accessible to the operator of said sewing machine, and abutment 30 means for said work piece attached to said movable means.

HENRY J. ERNST.
